to Square D Company, Detroit, Mich., a corpo-
ration of Michigan

Application December 31, 1946, Serial No. 135,874

Term of patent 14 years

(Cl. D57—1)

To all whom it may concern:

Be it known that I, Victor E. Carbonara, a citizen of the United States and a resident of Manhasset, county of Nassau, State of New York, have invented a new, original, and ornamental Design for a Binocular, of which the following is a specification, reference being had to the accompanying drawing, forming part thereof.

Figure 1 is a front elevational view of the binocular with the eyepieces at the top of the figure.

Figure 2 is a plan view from the eyepiece end of the binocular.

Figure 3 is a plan view from the objective end of the binocular.

I claim:

The ornamental design for a binocular, substantially as shown.

VICTOR E. CARBONARA.
